Fig. 4

Fig. 5

Fig. 6

Fig. 8

Fig. 7

Fig. 9

FIG. 1 is a front perspective view of one embodiment of an oxygen monitor embodying my new design;

FIG. 2 is a left side elevational view of the monitor shown in FIG. 1;

FIG. 3 is a rear elevational view of the monitor shown in FIG. 1;

FIG. 4 is a bottom plan view of the monitor shown in FIG. 1;

FIG. 5 is a top plan view of the monitor shown in FIG. 1;

FIG. 6 is a front perspective view of another embodiment of an oxygen monitor showing my new design;

FIG. 7 is a left side elevational view of the monitor shown in FIG. 6;

FIG. 8 is a rear elevational view of the monitor shown in FIG. 6; and

FIG. 9 is a bottom plan view of the monitor shown in FIG. 6.

I claim:

The ornamental design for an oxygen monitor, as shown and described.
